UNITED STATES PATENT OFFICE.

HENRY D. MILLS, OF INWOOD, NEW YORK.

WINDOW-SCREEN.

1,221,564.

Specification of Letters Patent.

Patented Apr. 3, 1917.

Application filed November 25, 1916. Serial No. 133,414.

To all whom it may concern:

Be it known that I, HENRY D. MILLS, a citizen of the United States, residing at Inwood, in the county of Nassau and State 5 of New York, have invented certain new and useful Improvements in Window-Screens, of which the following is a specification.

This invention has relation to window screens, and has for an object to provide a 10 screen of relatively movable sections, whereby the screen may be fitted to window openings of various widths.

Another object of the invention is to provide an adjustable window screen of the 15 character above set forth, and embodying a single strip of wire fabric or screening material, with means for taking up or paying out the strip as the screen sections are adjusted toward or away from each other.

20 A still further object of the invention is to provide a window screen having relatively adjustable frame sections, formed of pressed metal, and embodying means whereby the wire fabric may be inclosed within the frame 25 sections at the marginal edges of the fabric, and a rib on said frame sections whereby said sections may be guided and maintained in alinement during relative adjustment thereof.

30 In addition to the foregoing, my invention comprehends improvements in the details of construction and arrangement of the correlated parts to be hereinafter more fully described and particularly set forth in the 35 appended claims.

In the accompanying drawings in which similar and corresponding parts are designated by the same characters of reference throughout the several views in which they 40 appear;

Figure 1, is a view in front elevation of a window screen constructed after the manner of my invention.

Fig. 2, is a detail fragmentary view of one 45 corner of the screen.

Fig. 3, is a detail view illustrating the manner in which the spring roller is engaged and held, and

50 Fig. 4, is a transverse sectional view taken on the line 4—4 of Fig. 1.

With reference to the drawings, 10 and 11 indicate respectively the left and right hand sections of a window screen connected

for relative movement. The sections are in each instance rectangular with one side left 55 open, and the section 10, comprises an upper and lower horizontal frame member 12 and 13 respectively, and a vertical side member 14.

The frame section 10 is formed of pressed 60 metal, and in cross section the members thereof are formed of spaced sides 14 formed by doubling the metal at 15, with the free edges which constitute the inner edges of the frame section, bent outwardly, as at 16. The 65 portions 16 which are bent outwardly, however, extend to only a short distance from the member 14 of the frame along the inner edges of the frame members 12 and 13, and are adapted to form a stop for limiting the 70 movement of the frame section 11 in a manner which will be presently obvious. One of the portions 14 of the members 12, 13 and 75 14, of the frame section 10, is pressed outwardly to form a rib 17; having spaced inner sides, the ribs on the members 12 and 13 being provided adjacent their point of connection with the rib of the frame member 14 with a circular opening in one instance, and a rectangular slot 18 in the other 80 instance. The rectangular opening is however preferably provided in the ridge formed upon the lower frame members 13, and a spring roller preferably constructed of sheet metal, indicated at 19, is provided with a 85 circular trunnion 20 adapted to enter the aforesaid circular opening in the rib of the frame member 12, and a rectangular trunnion 21 which enters the aforesaid rectangular slot 18 in the lower rib. The keeper 22 90 is pivoted as at 23 to the rib upon the lower frame member 13, adjacent the journal of the spring roller, and said keepers are provided with a rectangular opening 24 in which to receive the aforesaid rectangular 95 trunnions 20 and 21 of the spring roller, whereby the said trunnion is effectively secured and held against rotation, said trunnion being thereby retained within the aforesaid rectangular opening 18. The keeper 100 22 is formed upon its upper edge with an inclined portion 25 the object of which will be presently noted.

The roller 19 as mentioned above is hollow, and provided with a central longitudinally extending rod 26 connected to the rec-

tangular trunnion 21, and a coil spring 27 is encircled about said rod and connected at one end to the rod and the opposite end to the interior of the roller. Said roller is also 5 provided upon its end adjacent the rectangular trunnion with a spur gear or ratchet wheel 28, and a pawl 29 is provided for engagement with said ratchet wheel. The aforesaid pawl 29 is formed of a single strip 10 of metal, bent upon itself, to provide spaced apertured arms or the like 30, adapted to engage opposite sides of the ribs upon the lower frame member 13, and an integrally formed finger piece 31 is extended laterally 15 from the pawl, whereby it may be raised or lowered into operative position. It will be noted by reference to Fig. 3, that when the pawl is moved to bring its connecting portion into engagement with the rib upon 20 which it is pivoted, through the medium of a pivot pin 32 with the rib and ears 30, the free end of the pawl is adapted to engage by its connecting portion between adjacent teeth of the aforesaid ratchet wheel 28 thereby retaining the wheel against rotation. The pawl is also formed with an inclined portion 33 which is adapted to engage the inclined portion 25 of the aforesaid keeper 25 whereby when the pawl is in the position 30 just referred to the keeper is retained in a position to secure the rectangular trunnion of the spring roller in place.

The screen section 11 is similarly formed of sheet metal, with the upper and lower 35 members 34 and 35 respectively thereof, as well as the vertical connecting member 36 formed of sheet metal of a double thickness indicated at 37, and with one of said thicknesses formed with a lateral longitudinally 40 extending rib 38. The inner marginal portions of the members 34, 35 and 36 of the frame section 11 are bent outward as at 39, and when the said sections 10 and 11 are brought into relation, the members 34 and 35 45 of the section 11 are adapted to enter the space between the spaced portion 14 of the members 12 and 13 of the section 10, whereby relative sliding or telescopic movement of the frame members is permitted. It is also 50 to be noted that the ribs 38 of said members 34 and 35, are adapted to enter the ribs 17 of the members 12 and 13, and the out-turned bars 39 of the screen section 11 receive the inner edges of the members 12 and 55 13 of the screen section 10, thus providing mutual guiding members to guide the frame sections 10 and 11 during relative adjustment thereof. It is also to be noted at this time that the similar out-turned portions on 60 the inner edges of the frame members 12 and 13, form a stop to limit movement of the frame section 11 by engagement with the out-turned margin 39 of said frame section 11, as clearly set forth in Fig. 1. The screen

material is in the nature of a strip of wire 65 fabric indicated at 40, with one end secured between the members of the element 36 of the frame section 11, with the marginal portions of said screen section 40 disposed within the space between the metallic strips comprising the members 34 and 35, and also the members 12 and 13, with the opposite end of the fabric wrapped about the spring roller 70 and secured thereto as at 41.

To adjust the screen to window openings 75 of different widths, it is but necessary to release the pawl 29 from engagement with the ratchet wheel 28, and then move the screen sections relatively, permitting the wire fabric to play out when the screen section 80 widens and to take up the material as the sections are moved toward each other to shorten the screen.

While I have illustrated and described my invention with some degree of particularity 85 I realize that in practice various alterations thereover may be made, and I therefore, reserve the right and privilege of changing the form of the details of construction or otherwise altering the arrangement of parts without departing from the spirit of the invention or the scope of the appended claims. 90

Having thus described my invention what I claim as new and desire to secure by Letters Patent is:—

1. A window screen including relatively 95 movable frame sections, said frame sections being formed of sheet metal with the members thereof of double thickness having one face thereof pressed outward to form a rib, 100 the ribs of the frame section being interengaged to form guides when the frame sections are moved relatively to adjust the screen, a spring roller mounted upon one section, a screen section mounted within the 105 frame, wrapped about the roller at one end, and having its opposite end secured to the opposite frame section, whereby to automatically take up or pay out the screen material as the frame sections are moved toward or away from each other, and releasable means for retaining the roller against movement subsequent to adjustment of the 110 screen sections.

2. A window screen, including relatively 115 movable frame sections, opposed ribs formed on one section having aligned openings, one of said openings being circular and the other rectangular extending to the edge of the rib, a spring roller having a cylindrical trunnion 120 at one end adapted to enter said circular opening, and a rectangular trunnion at the opposite end adapted to enter laterally a rectangular opening, a ratchet wheel secured to the spring roller, adjacent the end having the rectangular trunnion, a keeper pivotally secured to one rib for engaging the rectangular trunnion, to retain the same in place, 125

and a pawl formed of spaced connected members adapted to straddle the rib to engage opposite sides thereof and to be pivotally connected thereto, the free end of the 5 pawl having a lateral extension to form a finger grip, and for engaging between the teeth of the ratchet to retain the same against rotation, said pawl in this position

engaging the keeper to retain the same against displacement.

In testimony whereof I affix my signature 10 in presence of two witnesses.

HENRY D. MILLS.
